UNITED STATES PATENT OFFICE.

OTTO H. JOBSKI, OF CLEVELAND, OHIO, ASSIGNOR TO THE STANDARD PARTS COMPANY, OF CLEVELAND, OHIO, A CORPORATION OF OHIO.

RIM.

Application filed May 10, 1922. Serial No. 559,873.

To all whom it may concern:

Be it known that I, OTTO H. JOBSKI, a citizen of the United States, and a resident of Cleveland, county of Cuyahoga, State of Ohio, have invented certain new and useful Improvements in Rims, of which the following is a specification.

This invention relates to motor vehicle rims and more particularly to a locking means for the ends of a transversely split rim.

One of the objects of the invention is to provide a locking device that will be comparatively simple and inexpensive to manufacture and will be effective to prevent separation of the rim ends in any direction.

Other objects and the features of novelty will be apparent from the following description, taken in connection with the accompanying drawings, of which:

Figure 1 is a longitudinal section of a portion of a split rim embodying my invention, the section being taken on the line 1—1 of Fig. 2;

Fig. 2 is a plan view of the inner side of the same;

Fig. 3 is a perspective view of the latching tongue;

Fig. 4 is a view similar to Fig. 2 but showing another form of the invention; and

Fig. 5 is a perspective view of the latching tongue of the construction shown in Fig. 4.

Referring to the drawings, and particularly to Figs. 1 to 3, 10 and 11 indicate the opposite ends of a transversely split rim, the split being indicated at 12 and being preferably arranged at an angle of about 3° to the radial plane which is indicated by the line A. A latching tongue 13 is secured to the end 11 by rivets 14 or in any other suitable manner and comprises the end portions 15 and 16 which are adapted to contact with the inner surface of the rim ends, the tongue projecting across the split, as will be clearly seen from Figs. 1 and 2. Between the end portions 15 and 16 of the tongue there is a portion 17 which is offset outwardly to project into the opening or recess which is provided therefor at the split. From Fig. 1, it will be seen that this opening or recess extends into both ends of the rim so that the offset portion 17 bridges the split 12. From Fig. 2 it will be noted

that the tongue 13 holds the rim ends 55 against relative lateral movement and also in combination with the inclined split 12, holds the rim ends against relative radial displacement. It will be observed from Fig. 1 that the inclination of the split 12 is away 60 from the end 11 or that end to which the tongue 13 is secured.

A locking member or hook 18 is mounted on a pivot 19 on the end 10 of the rim and is adapted to overlie the offset portion 17 of 65 the tongue and cooperate with the projection on the end 15 to prevent circumferential separation of the rim ends. From Fig. 1 it will be noted that the inner surface of the offset portion 17, of the tongue, is flush 70 with the inner surface of the end 10 of the rim so that, when the parts are in the relation shown in Fig. 1, the hook 18 may be freely swung to and from a position of locking engagement with the tongue. 75

When the hook 18 is swung to the dotted position indicated in Fig. 2, the rim ends may be separated circumferentially or by subjecting the end 11 to a comparatively heavy blow on the exterior thereof, this end 80 may be forced inward beyond the end 10 so as to permit overlapping of the ends for the purpose of changing tires. When the parts are positioned, as shown in Figs. 1 and 2, however, the hook 18 prevents this radial 85 separation of the rim ends and also prevents the circumferential separation under the expanding action of the usual wedges with which the rim is clamped to the wheel. 90

In the form of the invention illustrated in Figs. 4 and 5, the tongue 20 is moved to the left from the position shown in Fig. 2 so that the opening for the offset portion 21 of the tongue is all in the end 10 of the rim. Moreover, the offset portion is not cut away, 95 as indicated at 22, in the offset portion 17 of the tongue illustrated in Fig. 3. In other respects the two forms are substantial and identical both in construction and function.

I prefer the form illustrated in Figs. 1 to 100 3 because it does not require as wide an opening in the end 10 of the rim and in this way does not weaken the ends as much as the construction illustrated in Fig. 4.

The latching tongues 13 and 20 are capable of being manufactured very economically because they can be produced from rolled bars, these bars being cut up into the

short lengths necessary to provide the tongues illustrated. The notch 22 may be cut on a stamping press.

Having thus described my invention, what I claim is:

1. In a transversely split rim, the combination of a tongue secured to one end of the rim and projecting across the split, the opposite end of the rim having a recess extending thereinto from the split and adapted to receive said tongue, and a member pivoted on said opposite end of the rim and adapted to interlock with said tongue to prevent circumferential separation of the rim ends.
2. In a transversely split rim, the combination of a tongue secured to one end of the rim and projecting across the split, the opposite end of the rim having a recess extending thereinto from the split and adapted to receive said tongue, said tongue having a projection extending radially inward from the portion which is received in said recess, and a locking member pivotally mounted on said opposite rim end and adapted to overlie said tongue and cooperate with said projection to prevent circumferential separation of said rim ends.
3. In a transversely split rim, the combination of a tongue secured on the inner side of one end of the rim and projecting beyond the split of the rim, the opposite end of the rim having a recess, said tongue having a portion thereof offset outwardly to enter said recess and said offset portion having its inner surface substantially flush with the inner surface of said opposite end of the rim and there being an inward projection on the end of said tongue, and a locking member on said opposite end of the rim adapted to overlie the inner surface of said offset portion of the tongue and cooperate with said projection to prevent circumferential separation of the rim ends.
4. In a transversely split rim, the combination of a tongue secured on the inner side of one end of the rim and projecting beyond the split of the rim, the opposite end of the rim having a recess, said tongue having a portion thereof offset outwardly to enter said recess and said offset portion having its inner surface substantially flush with the inner surface of said opposite end of the rim and there being an inward pro-

jection on the end of said tongue, and a locking member pivotally mounted on said opposite end of the rim and adapted to overlie the inner surface of said offset portion of the tongue and cooperate with said projection to prevent circumferential separation of the rim ends.

5. In a transversely split rim, having an opening therein at the split, a tongue having end portions adapted to engage the inner surface of the rim on opposite sides of the split and an intermediate portion offset radially outward to engage in said opening, and a pivoted locking member cooperating with said tongue to prevent circumferential separation of the rim ends.

6. In a transversely split rim, having an opening therein at the split, a tongue having end portions adapted to engage the inner surface of the rim on opposite sides of the split and an intermediate portion offset radially outward to engage in said opening, said tongue being rigidly secured to one end of the rim and having a projection on its inner side, and a locking member pivotally mounted on the opposite end of the rim and cooperating with said projection to prevent separation of the rim ends.

7. In a transversely split rim, the combination of a tongue secured to one end of the rim and extending across the split and having a part underlying the opposite end of the rim to prevent separation of the rim ends by moving said opposite end radially inward, the split being inclined relatively to a radial plane so that the first-mentioned end slightly overlaps the other end of the rim to normally prevent radially inward movement of the first-mentioned end.

8. In a transversely split rim, the combination of a tongue secured to one end of the rim and extending across the split and having a part underlying the opposite end of the rim to prevent separation of the rim ends by moving said opposite end radially inward, the split being inclined relatively to a radial plane so that the first-mentioned end slightly overlaps the other end of the rim to normally prevent radially inward movement of the first-mentioned end, and a locking member on said opposite end cooperating with said tongue.

In testimony whereof I affix my signature.
OTTO H. JOBSKI.
